UNITED STATES PATENT OFFICE

170,395

CAP FOR TUBE OR SIMILAR ARTICLE

Milton Brav, Chicago, Ill.

Application June 13, 1952, Serial No. 20,186

Term of patent 14 years

(Cl. D58—26)

To all whom it may concern:

Be it known that I, Milton Brav, a citizen of the United States, residing at Chicago, in the county of Cook and State of Illinois, have invented a new, original, and ornamental Design for a Cap for Tube or Similar Article, of which the following is a specification, reference being had to the accompanying drawing, forming part hereof.

Figure 1 is a top plan view of the cap for tube or similar article, showing my new design;

Fig. 2 is a side elevational view thereof; and

Fig. 3 is a bottom plan view thereof.

I claim:

The ornamental design for a cap for tube or similar article, substantially as shown.

MILTON BRAV.
